UNITED STATES PATENT OFFICE.

SAMUEL A. JONES, OF DESHLER, OHIO.

TILE-MAKING MACHINE.

No. 861,520.

Specification of Letters Patent.

Patented July 30, 1907.

Application filed March 15, 1906. Serial No. 306,235.

To all whom it may concern:

Be it known that I, SAMUEL A. JONES, a citizen of the United States, residing in Deshler, in the county of Henry and State of Ohio, have invented certain new and useful Improvements in Tile-Making Machines, of which the following is a specification, reference being had to the accompanying drawings, forming a part thereof.

My invention relates to improvements in machines for molding articles made of cement and other plastic materials, and particularly for making tiles for roofs and like structures; and one object of my invention is to provide a machine of this class which shall be simple in construction, cheap in manufacture and efficient in operation.

Another object of my invention is to provide a tile-making machine by means of which roofing tiles may be made either face up or face down.

A further object of my invention is to provide means for making tiles of special shape.

In the drawings illustrating the principle of my invention and the best mode now known to me of applying that principle, Figure 1 is a front elevation of my new machine; Fig. 2 is a sectional view on line A—A, of Fig. 1; Fig. 3 is a plan view of the mold; and Figs. 4, 5, and 6 are all detail views hereinafter referred to.

The table-bed *a* is supported by the usual standards *b* and in turn supports the mold-base *c* formed with four apertures *d* within which reciprocate plungers or pins *e* carried at the ends of the arms *f* which radiate from a common center *g* (see Fig. 2) and constitutes a spider. Over the central portion of the mold-base *c* is placed the false bottom *h* and around it closely fits the upper mold-body *j* adjustably mounted upon the three bolts *k* formed with square heads *m* which project below the table-bed and are adapted to be engaged and turned by means of an ordinary wrench. The upper mold-body *j* is formed with a rearwardly-projecting extension *n* which is supported by a bolt *o* similar to the bolts *k*, and upon which is adjustably mounted the hinge-base *p* secured thereto by bolts *q* and nuts *r*, said bolts extending through slots *s* formed in the hinge-base *p*. Integral with the hinge-base or block *p* are formed the hinge-posts or lugs *t* and the stop-lug *u*. In the hinge-lugs *t* is mounted a hinge-pin *v* fast upon which are the tamping-frame *w* formed upon its lower surface with the ribs *x*, and the rib-forming frame *y* provided with the slots *z* adapted to receive the ribs *x* (see Fig. 2). By loosening the nuts *r*, the hinge-block *p* may be moved upon the extension *n* to adjust the frames *w* and *y*. When the upper plate or the frame *w* is thrown back, its travel is limited by the stop-lug *u*.

The bolts *k* and *o* pass through the bed *a* and base *c* and serve not only to adjust the upper mold-body *j* for different thicknesses of tiles to be made, but they serve in combination with the locking nuts *3* also to

secure the upper mold-body *j* to the mold-base *c* and the latter to the table-bed *a*, as will clearly appear from an inspection of Fig. 2. The upper mold-body *j* is held rigidly in its adjusted position by the upper capstan locking-nuts *3*.

Upon the top of the false bottom *h* is placed a thin sheet-metal pallet 4 (Fig. 4) formed with ears 5 having holes 6 for the passage of core-pins 7 which serve to form the nail-holes in the ears of the tile. These core-pins are subject to wear at their upper ends by reason of the passing of the straight-edge in smoothing-up the material and striking off the excess. To allow for this wear the core-pins are screwed into the mold-base *c* (Fig. 5) and by turning them they may be adjusted to the proper height.

To raise the pallet 4 with its tile still wet and ready to be carried to the drying room, the following mechanism is provided: Fast upon one end of the shaft 8 is an arm 9, while fast upon its other end is a bevel gear 75 10 which meshes with the pinion 11 fast upon one end of a shaft 12, the other end of which carries a cam 13 that rubs against the center *g* from which radiate the arms *f* carrying the pins or plungers *e*, as above described (see Fig. 2). The travel or swing of the operating arm or handle 9 is limited by the stop-lugs 14, 15 which project from the adjacent standard. When the arm 9 is swung over against the stop-lug 14, the point 13^a of the cam or eccentric 13 is brought above the line or axis of the shaft 12 and forces the plungers *e* upwardly, thereby carrying the pallet 4 out of the mold 80 into position to be moved with the newly-molded tile to the drying room. The point of the cam is thrown over to a position which prevents the accidental lowering of the arm *f* and pins *e*.

Since my new machine is adapted to mold tiles either face up or face down, the corners 16, 17 of the upper mold-body *j* are both rounded; and the false bottom *h* may be removed and replaced by another designed and adapted to support the pallet 4 at all points 95 in the making of the tile by the particular process followed. The upper mold-body *j* is formed on its inner side faces with indentations 20, 21, 22, and 23, which serve to receive the ears 5 of the pallet 4. When the tile is made face down, the ears 5 fit into the indentations 20, 21 and plugs or filling pieces 24, 25 are inserted in the indentations 22, 23 to prevent the cement from entering therein; while when the tile is made face up, the ears 5 fit into the indentations 22, 23 and the plugs 24, 25 are used to fill in the indentations 20, 21. It will 100 be understood that the core-pins 7 are withdrawn to allow the insertion of the plugs 24, 25 and are passed upwardly through the ears 5 of the pallet 4 in whatever position the latter may be.

By making the tile face down, the operator is enabled to produce a tile having a figured surface or a surface complementary to the face of the pallet shown 110

in Fig. 4. Thus, a tile having its face divided in imitation of tiles of one fourth the size may be made and such tiles when placed in position will add greatly to the appearance of the roof. It is practically impossible 5 to make tiles of the size of the small subdivisions of the tile made face down on my machine and the effect can be obtained only by making the tiles face down. Further, the tile made face down with the subdivisions is a stronger tile by reason of the strengthening effect of the 10 ribs extending across the face of the tile. Another good result following the making of the tile face down lies in the fact that in such a tile the ears will have the full thickness of the tile, which is not possible in case of a tile made face up, the method heretofore in use. A 15 tile can be made face down in much less time than it takes to make a tile face up, for it is not necessary to smooth off the cement with such care.

In case it is desired to make a tile having one side formed to fit the line of a valley in a hip roof, an inset 20 piece 30, Fig. 6, is placed in the mold in the position indicated by the dotted lines in Fig. 3.

What I claim is:

1. In a molding machine of the character set forth, the combination with a table, of molding means mounted on 25 the table and having actuating devices disposed at one side of the same, a pallet associated with the molding means, a spider located beneath the table and having upstanding pallet engaging pins, a shaft journaled beneath the table and extending toward the side having the actuating devices 30 for the molding means, a cam on the inner end of the shaft that bears against the spider, a countershaft located beneath the side of the table on which the actuating devices are located and geared to the outer end of the first mentioned shaft, and an actuating device secured to the 35 outer end of the countershaft and disposed at one side of the actuating devices.
2. In a molding machine of the character set forth, the combination with a table, of a mold-base mounted thereon, a mold-body movably associated with the base, an 40 adjusting screw slidably engaged in the base and having their upper ends movably engaged with the body, relatively adjustable nuts threaded on the screw between the base and body and respectively engaging the upper face of the former and the under face of the latter for relatively 45 moving and holding the same, and molding mechanism associated with said body.
3. In a molding machine of the character set forth, the combination with a table, of a mold body located thereover and adjustable toward and from the same, adjusting 50 screws slidably engaged in the table and having their upper ends engaged in the body, nuts adjustably threaded on the screws between the body and table and bearing upon the latter, said nuts constituting adjusting means for the body and holding means for supporting the same at different 55 elevations, and molding mechanism associated with the body.
4. In a molding machine of the character set forth, the combination with a table having a bed, of a mold-base mounted thereon, a false bottom carried by the mold-base, 60 a mold-body surrounding the false bottom and located over

the base, a plurality of adjusting screws having their lower ends slidably passing through the table bed and base, and constituting means for securing the same together, said screws having their upper ends movably engaged in the mold-body, relatively adjustable holding nuts 6 threaded upon each screw between the base and body and respectively engaging the upper face of the former and the under face of the latter, said mold-body having an extension disposed over the table bed, an adjusting screw 7 slidably passing through the table bed and movably engaged with the extension, separate relatively adjustable nuts threaded on the screw between the extension and table bed, and respectively engaging the upper face of the latter and the under face of the former, and molding mechanism hinged to said extension and associated with the 7 mold-body.

5. In a molding machine of the character set forth, the combination with a support, of a mold-body mounted and vertically adjustable thereon, said body including an extension, a hinge block slidably mounted on the extension toward and from the mold-body, said extension and block being provided, one with a slot, the other with a clamp bolt passing therethrough and permitting the relative movement of the parts transversely and longitudinally of each other to hold the block against sliding movement and 8 in different positions, and molding means hinged to the block and associated with the body.

6. In a molding machine of the character set forth, the combination with a table and a mold-base mounted thereon, of a mold-body adjustably mounted thereon and having ear-forming sockets in its inner side, and core pins 90 passing through the table and threaded into the mold-base, said pins securing the table and base together and having unthreaded upper ends projecting into said sockets and constituting hole forming cores.

7. In a molding machine of the character set forth, the combination with a mold-base, of a mold-body adjustably mounted thereon and having a plurality of ear-forming sockets in each of its side walls, a reversible pallet that fits in the mold body and has a pair of ears that engage 10 in certain of the sockets accordingly as the pallet is reversed, and means for closing the sockets not occupied by the ears.

8. In a molding machine of the character set forth, the combination with a mold-base, of a mold-body adjustably mounted thereon and having a plurality of ear-forming sockets in each of its side walls, a reversible pallet that fits in the mold-body and has a pair of ears that engage in certain of the sockets accordingly as the pallet is reversed, means for closing the sockets not occupied by 11 the ears, and removable core pins placed in the sockets occupied by said ears.

9. In a tile-making machine, the combination of a pallet; a support therefor; and an upper mold-body having four sides the inner wall of each of which is formed with 11 an indentation; said pallet being formed with a pair of ears which fit into two of said indentations; and means for closing the pair of said indentations not occupied by the ears of said pallet.

In testimony whereof I hereunto set my hand this 120 twelfth day of March, 1906, at said Deshler in the presence of two witnesses.

SAMUEL A. JONES.
